DESIGN.

A. SEARLS.

Carriage Sole Trimmings.

No. 6,581.

Patented April 8, 1873.

UNITED STATES PATENT OFFICE.

ANSON SEARLS, OF NEWARK, NEW JERSEY.

DESIGN FOR CARRIAGE-POLE TRIMMING.

Specification forming part of Design No. 6,581, dated April 8, 1873; application filed January 16, 1873.

To all whom it may concern:

Be it known that I, ANSON SEARLS, of Newark, New Jersey, have invented and produced a new and original Design for Carriage Pole and Shaft Mountings, of which the following is a specification:

The manufacturers of carriages require the pole, neck-yoke, whiffletree, and shaft mountings to be of a general and uniform design, although they vary in form and size as regards the place where each may be used.

The photographic illustration shows a pole, neck-yoke, whiffletree, and shaft-tip.

A represents the mounting or tip of a carriage-pole, the forward end of which is heptagonal in form and the rear end cylindrical, with a re-enforcement of metal or band at the butt, the whole tapering gradually from butt

to point. B represents neck-yoke tips, being heptagonal from its outer end to the base of the pole-strap holder or guide nearest the butt, while the body of the tip from the strap-holder to the butt is cylindrical. E represents the whiffletree-tips, being heptagonal in form except a small portion near the butt, which is cylindrical. The tip is provided with lugs or ears upon its outer end to hold the button or eye. The tip is slightly tapering its entire length.

I claim as new in design—

The design for carriage-pole trimmings, as herein shown and described.

ANSON SEARLS.
